(57) **CLAIM**

The ornamental design for a combined boot, garment, and accessory dryer with boot and helmet attachments, as shown and described.

DESCRIPTION

FIG. 1 is a top front perspective view of a combined boot, garment, and accessory dryer with boot and helmet attachments, showing our new design;

FIG. 2 is a top rear perspective view thereof;

FIG. 3 is a bottom perspective view thereof;

FIG. 4 is a top view thereof;

FIG. 5 is a bottom view thereof;

FIG. 6 is a right side view thereof;

FIG. 7 is a left side view thereof;

FIG. 8 is a front view thereof; and

FIG. 9 is a rear view thereof.

FIG. 10 is a top front perspective view of a boot, garment, and accessory dryer with boot attachments and extended arms.

FIG. 11 is a top front perspective view of a boot, garment, and accessory dryer with helmet attachments and extended arms.

FIG. 12 is a front perspective view of a boot attachment;

FIG. 13 is a front view thereof;

FIG. 14 is a rear view thereof;

FIG. 15 is a top view thereof;

FIG. 16 is a bottom view thereof;

FIG. 17 is a right side view thereof; and

FIG. 18 is a left side view thereof.

FIG. 19 is a front perspective view of a helmet attachment;

FIG. 20 is a front view thereof;

FIG. 21 is a rear view thereof;

FIG. 22 is a left side view thereof;

FIG. 23 is a right side view thereof;

FIG. 24 is a top view thereof; and

FIG. 25 is a bottom view thereof.

(Continued)

The broken lines shown in the figures are for the purpose of illustrating portions of the combined boot, garment, and accessory dryer with boot and helmet attachments and form no part of the claimed design.
